UNITED STATES PATENT OFFICE.

RALPH M. LOVEJOY, OF MEREDITH, NEW HAMPSHIRE.

CARBURETER.

1,277,963.

Specification of Letters Patent.

Patented Sept. 3, 1918.

Application filed October 22, 1914. Serial No. 868,112.

To all whom it may concern:

Be it known that I, RALPH M. LOVEJOY, a citizen of the United States, and resident of Meredith, county of Belknap, State of New Hampshire, have invented an Improvement in Carbureters, of which the following description, in connection with the accompanying drawing, is a specification, like characters on the drawing representing like parts.

10. This invention relates to improvements in carbureters of the type which is especially adapted to internal combustion engines. One of the objects of the invention is to provide means for speedily and certainly vaporizing the combustible fluid which is supplied to the carbureter so as to provide a suitable explosive mixture of the highest efficiency, and to prevent the introduction into the cylinder of any of the combustible fluid. 15. Another object of the invention is to provide means for automatically regulating the amount of fluid supplied in proportion to the air introduced into the cylinder whereby a perfect mixture may be obtained. 20. Another object of the invention is to provide a gravity feed for the combustible fluid which may be controlled by the intake of the air. 25. Another object of the invention is to provide means for opening and closing the throttle which governs the air intake in such a manner that greater leverage may be applied to the throttle at the initial opening of the same than is thereafter applied during 30. the regulation of said throttle. 35. Other objects of the invention will more fully appear from the following description read in connection with the accompanying drawing which will illustrate one of the 40. means in which the invention may be embodied and will be pointed out in the annexed claims.

The drawing represents a vertical longitudinal sectional view of one of the preferred forms of apparatus for embodying my invention.

The apparatus as illustrated in the drawing comprises a main casting 1 which may be provided with suitable means for supporting the same and securing it in proper relation to the engine, the casting 1 being provided with an internal bore 2 forming an air conduit leading to the mixing chamber 3 which may be connected in the usual manner with the cylinders of an internal combustion engine. The casting 1 may be pro-

vided at its upper portion with a longitudinally extending boss 4 provided with a feeding duct 5 terminating in an annular well 6 surrounding the opening 7 leading from the main conduit 2 to the carbureting chamber 3. The carbureting chamber may conveniently be formed of a tubular casing 8 having a tapered inwardly extending annular wall 9 at its lower end adapted to register with and to approach closely to the opening 7 leading from the main conduit to the carbureting chamber so as to provide a narrow, extended, preferably annular aperture adapted to feed a thin film of the combustible liquid into the path of the incoming current of air in the manner which will more fully be described.

The opening 7 is provided with a throttle 10 preferably in the form of two oppositely arranged and desirably integral conoidal members having guiding stems, the upper stem being journaled in a suitable bearing 12 in a spider 13 carried by the casing 8 of the air chamber, the lower stem 14 passing through a boss 15 extending upwardly from the lower portion of the casing. The throttle 10 is normally maintained in closed position by a spring 16 surrounding the stem 14 and the boss 15 and pressing at its ends 17 respectively upon the casing and the lower end of the throttle 10.

The double conoidal form of the throttle is adapted to deflect the inrushing current of air in such a manner as to diffuse the same in the carbureting chamber and thereby to cause a thorough carbureting of the combustible fluid so that the heavier oils such as kerosene and the like may be utilized.

Suitable means may be employed for regulating the position of the throttle as will be hereinafter more fully described.

In most of the carbureters now employed the combustible fluid is fed to the carbureting chamber either by a forced feed or its flow is induced by suction which draws the same directly from the reservoir containing it.

One of the objects of the present invention is to provide for a purely gravity feed of the combustible liquid in which the flow is not abnormally increased by the suction induced by the air entering the carbureting chamber, and this apparatus is so designed that the combustible fluid will at all times be under the influence of a certain predetermined head and none other. In order to

effect this purpose I provide an opening which may be in the form of a conduit 17 leading from the atmosphere to the fluid conduit 5 or well 6, this opening providing 5 not only means for preventing suction upon the reservoir through the conductor 5 but also permitting an intake of air to the mixing chamber in conjunction with the supply of fluid, thereby facilitating the feeding of 10 the fluid and aiding in its vaporization.

The reservoir for the combustible fluid is preferably in the form of a tank 18 which may be supplied through the pipe 19 from the usual reservoir, the supply of fluid being 15 controlled by a valve 20 seated in the lower end of the inlet 19 and governed by a float 21 which may be conveniently mounted upon the valve stem 22 of said valve, the lower end of said valve stem being guided in a 20 suitable bearing in a boss 23 depending from the bottom of the reservoir 18.

The supply of oil to the conductor 5 may be regulated by a valve 24 having a tapered end 25 adapted to seat upon a corresponding 25 tapered valve seat in the upper end of the conductor 5, the said lower end being inclosed in an enlarged end 26 leading from the reservoir 18.

The valve 24 is desirably provided with 30 an enlarged stem 27 journaled in a suitable bearing in the side wall of the reservoir 18 and the lower end of the valve is of a preferably tapered or conical form 28 adapted to coöperate with the entrance 29 into the 35 chamber 26 and thereby to regulate the amount of fluid delivered from the reservoir 18 to the conductor 5 when the valve is raised so that its end 25 is removed from its seat at the upper end of said conduit. The upper 40 end of the valve stem 27 is desirably provided with an extension 30 having adjustable check nuts 31, 32 arranged upon opposite sides of a lever 33 which is attached through a link 34 to the stem 35 of a plunger 45 36 which is normally pressed downwardly to close the valve by a spring 37. The plunger 36 may desirably be disposed within a casing 38 within the reservoir 18 and having an opening 39 leading to said reservoir whereby 50 the plunger 36 within the casing 38 is in effect a dash-pot adapted to prevent the hammering of the valve.

The lever 33 at its opposite end 40 may bear upon the underside of the nut 41 upon 55 the stem 42 of a valve 43 which fits closely the cylindrical inlet 44 of the conduit 2. The valve stem 42 may be mounted at its lower end in a boss 45 in the lower wall of said conduit and at its upper end in a boss 60 46 carried by a preferably arched spider 47 which may be secured by bolts or screws 48 and suitable laterally extending flange 49 at the intake end of the conduit 4.

By the construction above described the 65 suction through the mixing chamber 3

caused by the action of the engine cylinders will induce a current of air through the conduit 2 which by reason of the form of the throttle valve 10, which closely fits the opening 7, will be in the form of a thin, preferably annular blast of air which will rush at a high velocity through the narrow opening between the wall of the aperture 7 and the edge of the throttle at the point at which the combustible fluid is supplied, thus causing the fluid to be rapidly and completely vaporized. The partial vacuum thus created in the conduit will draw down the valve 43 beyond the end of the cylindrical portion 44 into the conical portion 44^a of the inlet opening and permit a greater supply of air in proportion to the amount of air required by the engine. 75

The depression of the valve 43 will force down the end 40 of the lever 33 thereby raising its opposite end and thereby lifting the valve 24 from its seat and permitting the combustible fluid to flow through the conductor 5 to the well 6 of the carburetor. By reason of the conical portion 28 of the valve 90 24 and its relation to the opening 29 into the chamber 26 which leads to the conduit the amount of combustible fluid supplied will be regulated in proportion to the amount of air which passes through the conduit 2. 95

Upon the shutting down of the engine the suction through the mixing chamber 3 will cease and the valve 44 will be returned to its initial position as illustrated in the drawing through the influence of the spring 37, simultaneously therewith the spring 37 will seat the end 25 of the valve 24 upon its seat at the upper end of the conductor closing off the supply of combustible fluid to the 105 well 6.

The diameter of the throttle preferably is slightly less than the diameter of the opening 7 leading from the conduit 2 to the carbureting chamber so that the engine may 110 be supplied with a sufficient amount of air to run idly at a slow speed, the area of this opening being varied when the engine is working in the manner heretofore described. 115

It is desirable when starting that a greater leverage be provided for opening the throttle than during the subsequent regulation thereof and in order to provide for this contingency I have provided a series of 120 levers which will give an increased leverage at the opening of the throttle and a gradually decreasing leverage thereafter.

As illustrated herein the lever which is connected to the stem 14 of the throttle is 125 in the form of a bell crank 50 journaled upon a suitable bracket 51 depending from the casing, one arm of said lever engaging a suitable head 52 upon the end of the 130 throttle stem 14 and the other arm of the

lever being provided with a relatively long substantially straight bearing portion 53 adapted to be engaged by the arc shaped end 54 of a lever 55 journaled in suitable brackets 56 extending from the side of the casing, the upper end of the lever 55 being connected by a rod 57 to a suitable hand lever under the control of the operator, such for example as a lever upon the steering 10 wheel of an automobile.

In order that the uppermost or closed position of the throttle may be accurately determined the bracket 51 is desirably provided with an extension 58 forming a bearing 15 for a setscrew 59 which may be adjusted to engage the bell crank lever and determine its normal position.

By the construction above described it will be obvious that the initial movement 20 of the lever 55 will cause the opening of the valve under the influence of the longer leverage thereby causing the valve to open with relative ease and when opened the subsequent movement of the valve will be controlled through the rocking connection between the parts 53 and 54 in such a manner that the throttle may be accurately adjusted.

It is to be understood that the embodiment of the invention disclosed herein is illustrative merely and that the invention may be embodied in other forms within the scope of my invention as set forth in the following claims.

Having thus described my invention what I claim as new and desire to secure by Letters Patent is:

1. In a carbureter comprising a carbureting chamber and a fuel reservoir, means for supplying a restricted current of air to said carbureting chamber, means for delivering at atmospheric pressure a thin film of liquid fuel from said reservoir into the path of said current of air whereby said liquid fuel will be rapidly vaporized and mixed with said air in the carbureting chamber.

2. In a carbureter comprising a carbureting chamber having an inlet, a throttle in said inlet adapted to restrict the area thereof to a narrow aperture, means for supplying a current of air at high velocity through said aperture, a fuel reservoir and means for delivering by the action of gravity and at atmospheric pressure a thin film of liquid fuel into the path of the current of air at said inlet aperture.

3. In a carbureter a carbureting chamber having an annular inlet, a throttle in said inlet adapted to restrict the area thereof to a narrow annular aperture, means for supplying a current of air at high velocity through said annular aperture, a fuel reservoir located at a higher level than said inlet, a conduit leading from said reservoir

to said inlet and having means for delivering a thin film of liquid fuel in the path of the current of air at said inlet and a vent leading from said conduit to the atmosphere.

4. In a carbureter, a carbureting chamber having an inlet, a throttle in said inlet adapted to restrict the area thereof to a narrow aperture, means for inducing a current of air at a high velocity through said inlet, means for delivering a thin annular film of combustible fluid in the path of the air at said inlet, means for regulating said throttle to vary the amount of air supplied to said carbureting chamber and means independent of said throttle operable by the variation of the air supplied to correspondingly vary the amount of fluid delivered.

5. In a carbureter, a carbureting chamber having an inlet, an air conduit leading thereto, a throttle in said inlet adapted to restrict the area thereof to a narrow extended aperture, means for inducing a current of air at a high velocity through said inlet, means for delivering a thin annular film of combustible fluid in the path of the air at said inlet, means for regulating said throttle to vary the amount of air supplied to said carbureting chamber, means independent of said throttle operable by the variation of the air supplied to correspondingly vary the amount of fluid delivered comprising a valve in the intake end of said conduit and means operated thereby to control the fluid delivery.

6. In a carbureter, a carbureting chamber having an inlet, an air conduit leading thereto, a throttle in said inlet adapted to restrict the area thereof to a narrow extended aperture, means for inducing a current of air at a high velocity through said inlet, means for delivering a thin annular film of combustible fluid in the path of the air at said inlet, means for regulating said throttle to vary the amount of air supplied to said carbureting chamber, means independent of said throttle operable by the variation of the air supplied to correspondingly vary the amount of fluid delivered comprising a valve in the intake end of said conduit and a valve in the fluid supply pipe operable thereby to regulate the delivery of the fluid.

7. In a carbureter, a carbureting chamber having an inlet, an air conduit leading thereto, a throttle in said inlet adapted to restrict the area thereof to a narrow aperture, means for inducing a current of air at a high velocity through said inlet, means for delivering a thin annular film of combustible fluid in the path of the air at said inlet, means for regulating said throttle to vary the amount of air supplied to said carbureting chamber, means operable by the variation of the air supplied to correspondingly

vary the amount of fluid delivered comprising a valve in the intake end of said conduit, a valve in the fluid supply pipe operable thereby to regulate the delivery of the 5 fluid, and spring actuated means for closing the fluid regulating valve upon the shutting off of the air supply.

8. In a carbureter, a carbureting chamber having an inlet, an air conduit leading 10 thereto, a throttle in said inlet adapted to restrict the area thereof to a narrow aperture, means for inducing a current of air at a high velocity through said inlet, a reservoir, means for delivering a thin annular 15 film of combustible fluid from said reservoir into the path of the air at said inlet, means for regulating said throttle to vary the amount of air supplied to said carbureting chamber, means operable by the variation 20 of the air supplied to correspondingly vary the amount of fluid delivered comprising a valve in the inlet conduit, a valve in the fluid supply pipe operable thereby to regulate the delivery of the fluid and a 25 spring-actuated plunger in said reservoir acting as a dash-pot to close said fluid regulating valve upon the shutting off of the air supply.

9. In a carbureter, a carbureting chamber 30 having an inlet, a throttle in said inlet

adapted to restrict the area thereof to a narrow aperture, means for inducing a current of air at a high velocity through said inlet, means for delivering a thin film of combustible fluid in the path of the air at 35 said inlet, means for regulating said throttle to vary the amount of air supplied comprising a series of levers arranged to provide greater leverage for the initial movement 40 of the valve than for subsequent movement thereof.

10. A carbureter comprising a carbureting chamber having a restricted air inlet, means for delivering a combustible fluid thereto, a throttle adapted to vary the area of said 45 air inlet, means for actuating said throttle including a bell crank lever connected to said throttle and a coöperating actuating lever having rocking engagement with said throttle lever arranged to produce a progressively decreasing leverage thereupon 50 as the throttle is opened and means for operating said actuating lever.

In testimony whereof, I have signed my name to this specification, in the presence of 55 two subscribing witnesses.

RALPH M. LOVEJOY.
